UNITED STATES PATENT OFFICE.

WILLIAM H. HOLT, OF PROVIDENCE, RHODE ISLAND.

SNAP FASTENER.

Application filed December 27, 1921. Serial No. 525,095.

To all whom it may concern:

Be it known that I, WILLIAM H. HOLT, a citizen of the United States, residing at Providence, in the county of Providence and State of Rhode Island, have invented 5 certain new and useful Improvements in Snap Fasteners, of which the following is a specification.

This invention relates to snap fasteners 10 of the class adapted for heavy work, such for instance as on automobile curtains, rubber coats, leather goods and the like, and the object of this invention is to improve and simplify such a construction of fastener in which a locking jaw is mounted 15 and is adapted to be manually operated to release the fastener without applying force to disconnect it from its post thereby preventing tearing of the goods to which 20 the fastener is attached.

With these and other objects in view, the invention consists of certain novel features of construction, as will be more fully described, and particularly pointed out in 25 the appended claims.

In the accompanying drawings:—

Figure 1 is a plan view of my improved fastener with the top of the casing removed showing the operating mechanism mounted on the lower plate.

Figure 2 is a sectional side elevation of the top member of the casing showing the bendable attaching fingers.

Figure 3 is a sectional side elevation on 35 line 3—3 of Figure 2 showing the bottom member of the casing with the lugs raised from its stock.

Figure 4 is a perspective view of the jaw member of my improved fastener.

Figure 5 is a central sectional elevation 40 showing my improved fastener as mounted on a heavy piece of goods and connected to a retaining post or stud member.

It is found in practice that where the 45 ordinary snap fastener of this character is employed on heavy work, such as on automobile curtains and the like which must be pulled to release the fastener from its stud member, that the spring, which must 50 necessarily be rather heavy on this type of fastener, is usually so stiff that in order to release the fastener by pulling, the goods to which the fastener is attached are often torn. To obviate this difficulty I have pro-

vided an improved form of fastener with a 55 laterally movable releasing jaw adapted to be manually operated to release the fastener from the stud member thereby permitting the fastener to be removed from the stud without pulling or straining the material 60 to which it is attached, and the following is a detailed description of one construction of fastener by which this result may be accomplished:—

With reference to the drawings, 10 designates the bottom plate of the casing on which the operating mechanism is mounted, the center of this plate being provided with an opening 11 and on the face of this plate are raised two lugs 12 by shearing 65 the stock of the plate, which lugs serve as guides for the locking jaw 13.

This locking jaw is also preferably constructed from sheet stock and is provided with a forwardly-extending, stud-engaging 70 member 14 which is adapted to slide freely between the posts 12, and this jaw is provided with two laterally-extending wings 75 15 which engage the posts 12 to limit the inward motion of the jaw. On this jaw 80 I have also cut from the stock and bent upwardly, an operating handle member 16 and in cutting this handle member from the stock at the rear of the jaw, I have formed a recess 17 therein for the reception 85 of the looped portion 18 of the operating bow spring 19.

On this base plate 10 I have also cut and raised a pair of lugs 20 which engage the opposite outer ends of this bow spring, to 90 cause it to exert a closing tension on the jaw member 14. By forming a loop in this spring and causing it to extend into the recess 17 in the rear of the jaw member this spring is held against a relative endways 95 movement and is free without other fastening to act against the jaw member to carry it back into engaging position after having been pressed outwardly therefrom.

The upper member 21 of this casing is 100 formed somewhat cup-shape to set over and inclose the operating mechanism and is provided in its upper wall with a slot 22 through which the operating handle 16 of the jaw extends and which cooperates with 105 the guide lugs 12 to guide the movement of the jaw to and from operating position.

This upper casing is provided on its

edges with a plurality of comparatively short fingers 23 which are adapted to extend through the slots 24 in the bottom plate and be clinched thereunder to bind the top 5 and bottom members of the fastener casing together.

This upper casing member is also provided with a plurality of longer fingers 25 which are adapted to extend through the 10 slots 26 in the bottom plate, and also through the fabric 27, to be clinched as at 28 beneath the bottom washer 29.

On the outer end of the operating handle 16 I preferably mount a round headed cap 15 30 which is easy to be engaged by the thumb or finger to withdraw the jaw and which also prevents catching of the adjacent parts on the handle.

My improved snap fastener is constructed 20 to be attached to the grooved end 31 of a stud member 32, the same being of suitable size to pass through the central opening into the casing and the groove in the stud being shaped to receive the jaw 14 of the 25 fastener whereby the fastener is securely locked thereto.

Such a stud may be secured to the base 33 by any desired means but I have shown 30 a screw post 34 on the end of the stud by which it may be secured in position to the base.

My improved snap fastener is extremely simple and practical in construction and effective in its operation and by its use a 35 curtain or other member to which it is fastened may be released from the stud on the adjacent member, by simply moving the operating handle of the jaw outwardly or from the groove in the stud thereby completely releasing the fastener without the 40 necessity of pulling, tearing or ripping the goods on which it is mounted which is ordinarily the case where a manually operable releasing jaw is not employed.

The foregoing description is directed 45 solely towards the construction illustrated, but I desire it to be understood that I reserve the privilege of resorting to all the mechanical changes to which the device is susceptible, the invention being defined limited only by the terms of the appended 50 claims.

I claim:

1. A snap fastener comprising a circular casing, a gripping jaw in said casing bodily 55 slideable radially to and from operating position, an operating handle extending through a guide slot in the top wall of said casing, integral guide lugs raised from the stock of said casing arranged to cooperate 60 with said handle in its guide slot for guiding the movement of said jaw and limiting the extent of its inward stroke, and a spring acting to return the jaw after it has been withdrawn from engaging position. 65

2. A snap fastener comprising a casing, a laterally-slidable gripping jaw in said casing, an operating handle on said jaw extending through said casing, guides for said jaw in said casing arranged to also limit 70 the movement of said jaw towards gripping position, a spring acting between said jaw and casing to return the jaw after it has been withdrawn from engaging position, and means in said jaw for engaging and 75 preventing a relative endways movement of said spring.

3. A snap fastener comprising a casing, a laterally-slidable gripping jaw in said casing, an operating handle on said jaw extending through the top of said casing, 80 guides in said casing for limiting the movement of said jaw, said jaw being provided with a recess in its outer edge, and a bow-spring having a central offset loop entering 85 said recess to position the spring and prevent relative endways movement thereof.

4. A snap fastener comprising a separable casing, a laterally-slidable gripping jaw in said casing and having an operating handle extending through a guide slot in the top wall of said casing, guide lugs in said casing arranged to cooperate with said handle in its guide slot for controlling and limiting the movement of said jaw, said jaw 95 being provided with a recess in its outer edge, and a bow spring for closing said jaw and having a central offset loop entering said recess to position the spring and prevent relative endways movement thereof. 100

In testimony whereof I affix my signature.

WILLIAM H. HOLT.
